UNITED STATES PATENT OFFICE.

ISAAC BERKOWITZ, OF NEW YORK, N. Y.

DESIGN FOR A LENS.

61,029.

Specification for Design.

Patented June 6, 1922.

Application filed September 16, 1921. Serial No. 501,203. Term of patent 7 years.

To all whom it may concern:

Be it known that I, ISAAC BERKOWITZ, citizen of the United States, residing at New York, in the county of New York and State of New York, have invented a new, original, and ornamental Design for Lenses, of which the following is a specification, reference being had to the accompanying drawing, forming a part thereof.

Figure 1 is a plan view of a lens showing my new design; and

Figure 2 is a section thereof on line 2—2 of Figure 1.

I claim:

The ornamental design for a lens, as shown.

In testimony whereof I affix my signature.

ISAAC BERKOWITZ.
